UNITED STATES PATENT OFFICE.

MAX POETZSCH, OF RIDGEWOOD, NEW JERSEY.

TEASEL-CLEANING MACHINE.

Application filed June 22, 1923. Serial No. 647,106.

To all whom it may concern:

Be it known that I, MAX POETZSCH, a citizen of the United States, and a resident of Ridgewood, in the county of Bergen and State of New Jersey, have invented a new and Improved Teasel-Cleaning Machine, of which the following is a full, clear, and exact description.

This invention relates to machinery used in the manufacturing of nap goods and particularly to an improved teasel cleaning machine and has for an object to provide a construction which will automatically clean a series of teasels in a minimum time.

Another object of the invention is to provide a machine wherein an entire frame of teasels may be cleaned at one operation automatically.

A still further object of the invention is to provide a cleaning apparatus in which brushes and suction are utilized for cleaning the teasels.

In the accompanying drawings—

Figure 1 is a side view of one end of the teasel cleaning machine embodying the invention.

Figure 2 is a side view of the other end of the teasel machine to that shown in Figure 1.

Figure 3 is a top plan view of that part of the teasel machine shown in Figure 1.

Figure 4 is a top plan view of that part of the teasel machine shown in Figure 2.

Figure 5 is a transverse sectional view through Figure 1, approximately on line 5—5, the same being shown on an enlarged scale.

Figure 6 is a transverse sectional view through Figure 2, approximately on line 6—6, the same being shown on an enlarged scale.

Figure 7 is an enlarged fragmentary sectional view through Figure 2, approximately on line 7—7.

Figure 8 is a fragmentary sectional view through Figure 2 on line 8—8.

Heretofore, in the use of teasels, it has been customary to arrange a number of teasels in a frame and to use these teasels for raising the nap on certain goods. When the teasels are in use, it is customary to have the goods on which they are used moist or wet and, consequently, the teasels become wet during continued use and also become clogged or filled with the nap pulled from the cloth. After a certain amount of use,

it is necessary to remove the teasels, clean them and then place them in a drying room to be thoroughly dried before they can be again used. Heretofore, the cleaning operation required an appreciable amount of time and then the frames, with the teasels therein, were placed in racks in suitable drying rooms and left until dried, which would take from several hours to a day. This necessitates not only a large sum of money but presents an unpleasant dusty work, more or less unhealthy for the men who perform the cleaning operation. When the work was done manually, the pressure exerted on the teasels was not uniform and, consequently, an appreciable number of teasels were injured whereas in the present structure the pressure and other action are even and may be adjusted to suit various conditions whereby the teasels are not only cleaned but better preserved.

In the present invention, a construction has been presented which quickly cleans the teasels while wet so that they are ready for use in a very short time, the operation being continuous from the time the teasel carrying frame is inserted into the machine until it is discharged ready for use.

Referring to the accompanying drawings by numeral, 11 indicates a frame of any desired kind, preferably of angle iron supplied with suitable braces and other members for carrying the various parts of the machine. The frame 11 has mounted thereon four sprocket wheels, namely, sprocket wheels 12, 13, 14 and 15, said sprocket wheels carrying a chain 16 to the links of which are secured at suitable intervals hook-shaped stops 17, said stops being placed far apart to readily place a frame 18 between any two stops. The sprocket wheels 12 and 13 are preferably so positioned that the upper run of the chain is a short distance above the top of the frame 11 and preferably passes over a U-shaped supporting guide 19, which guide is cut away at the bottom near the ends to permit the chain to pass through.

As indicated in Figure 7, this guide permits the chain to freely move but prevents any appreciable wobbling and also acts as a lateral support for the respective frames 18 which are placed on the chain between the sides 20 and 21 so that the various teasels 22 will be held upright as the stops 17 are pushed against the ends of the frames. It will be noted that the frames 18 are of the

usual constructions which are now in common use and consist of a pair of side plates held by screws or other means and forming long sockets for receiving the stems of the various teasels 22. The stems are squeezed firmly by the frames so as to hold the same in place until released.

During the operation of the machine, the respective frames are placed in the guide 19 near one end and the frames move along by the chain 16. During the movement of the respective frames 18, the teasels thereon pass the cleaning belts 23 and 24 and then pass the cleaning rollers 25 and 26, said rollers being provided with bristles of some desired type. The belts 23 and 24 are formed as aprons of special card cloth and act to loosen woolen flakes or ravelings which have been tightly pressed or embedded in the teasels and held therein by the hooks of the teasels.

Card cloth is a well known article used in cloth manufacturing establishments and consists of a special body or support with small hook members projecting therefrom and positioned in a compact body. The action of the hook members of the card cloth as the belts or aprons 23 and 24 move past the teasels is to loosen the ravelings caught therein and in fact, to loosen all parts of the teasels. Very little of the ravelings are removed by the card cloth but what little is removed may in turn removed from the card cloth aprons or belts 23 and 24 by brushes 27 and 28 positioned to clean the aprons 23 and 24 continually so that the card cloth will be clean as it engages the respective teasels. Preferably, the part of each of the aprons 23 and 24 arranged in contact with the teasels, moves in a direction opposite to the movement of the teasels and also the brushes 27 and 28 revolve in a direction opposite to the direction of movement of that part of the aprons which pass these brushes. By arranging the parts in this manner, a thorough cleaning action is provided both for the teasels and for the cleaning aprons 23 and 24.

It will be understood that the frame 18 with the teasels mounted therein will move along at the speed of the chain 16 and, consequently, will gradually pass between the respective card cloth aprons 23 and 24 and into position between the roller brushes 25 and 26. The side members 20 and 21 of the guide 19 are cut away opposite the brushes 25 and 26 so that these brushes may freely engage the sides of the teasels for using a second cleaning action. These brushes are connected with shafts 29 and 30, which shafts carry sprocket wheels at one end for accommodating the respective chains 31 and 32 which pass over suitable sprocket wheels secured to the respective shafts 33 and 34, which shafts are driven

as hereinafter fully described. By these means, the brushes 25 and 26 are continually rotated and in order that these brushes may act from the top to the bottom of the teasels, the brushes are given an up and down motion in addition to the rotary motion. This up and down motion is produced by having the ends of the shafts 29 and 30 journaled in suitable bearing boxes 35 and 36 which are provided with downwardly extending sections 37 and 38. As all of these members are identical, the description of one set will apply to all.

As shown particularly in Figure 6, the sections 37 and 38 freely slide in guides 39 and 40 carried by the frame and are pivotally connected at 41 and 42 to the rods 43 and 44 having on their ends eccentric straps 45 and 46. These eccentric straps accommodate eccentrics 47 and 48 which are rigidly secured to the shafts 49 and 50. As the shafts 49 and 50 extend full length of the brushes 25 and 26 and act on the eccentrics at each end as illustrated in Figures 1 and 2, the brushes 25 and 26 will be moved upwardly and downwardly at each end simultaneously and as they are rotated by the chains 31 and 32 and associated parts, a thorough cleaning action from top to bottom of the teasels will take place.

From Figure 5 it will be noted that the shafts 49 and 50 are rotated by the worm gears 51 and 52 which are rigidly secured thereto, said worm gears being in turn driven by the worms 53 and 54 rigidly secured to the shaft 55. The shaft 55 carries a bevel gear 56 at one end which meshes with the bevel gear 57 rigidly secured to the shaft 33, which shaft is driven by power from any suitable source through the pulley 58. As the teasels leave the brushes 25 and 26, they pass between final cleaning brushes 59 and 60 operating on vertical spindles. After leaving these brushes, the teasels are subjected to a blowing action through the cup 61 which is supplied with compressed air by any suitable means. The air pump or other air supply acts through the tube 62 and thereby provides an ample space of air for the cup 61 to finish the cleaning action on the teasels.

After the frame carrying the teasels has moved past the cup 61 it moves onto the top run of a belt conveyor 63 which continues to move the frame until it strikes the end 64 of lever 65, which lever is bifurcated at the upper part and is pivotally connected at 66 to the rod 67. The lever 65 is maintained in the position shown in Figure 2 normally by a spring 68 but when end 64 is moved by the frame 18, the lever swings and moves the clutch member 69 into engagement with the clutch member 70 as lever 65 is connected with the clutch member 69 and said clutch

member in turn is splined on the shaft or axle 71. The clutch member 70 is continually rotating as it is connected to a suitable sprocket wheel 72 operated by the chain 73, which chain is operated by sprocket wheel 74. The sprocket wheel 74 is connected by the bevel gear 75 (Figure 4) which in turn is actuated by the bevel gear 76, which latter gear is rigidly secured to shaft 77 and said shaft in turn is rigidly connected with the drum 78 on which the belt 63 is mounted. The opposite end of the belt 63 is mounted on a suitable drum 79 which is rigidly secured to the shaft 80 carrying the sprocket wheel 81. A chain 82 is carried by the sprocket wheel 81 and is operated by sprocket wheel 83 secured to the shaft 84, which shaft is rigidly secured to the sprocket wheel 13 operated by chain 16.

By the mechanism just described, the clutch member 70 is continually rotated and, consequently, whenever the clutch member 69 is thrown into action, power will be immediately applied to the shaft or axle 71 for rotating the same. The direction of movement of the sprocket wheel 72 is such as to cause the shaft 71 to move in such a direction that the rods 67 and 67' will swing the pusher bar 85 as shown in dotted lines in Figure 8 and, consequently, will push the frame 18 off of the belt 63 and onto the chute or guide 86 along which it travels under the action of gravity until it is discharged.

From the mechanism described, it will be seen that a wet set of teasels full of ravelings is placed in the machine and these teasels are cleaned and discharged.

In the accompanying drawings, the power is shown as being received through the pulley wheel 58 from any suitable source, said pulley wheel acting to drive the shaft 33, which shaft extends for the full length of the frame 11. Near the front of the frame a transverse shaft 88 is provided which is connected to shaft 33 through the bevel gears 89 and 90, shaft 88 having a sprocket wheel 91 secured thereto for driving the chain 92 which passes over a sprocket wheel 93 rigidly secured to the shaft 94, which shaft also carries the sprocket wheel 15. By this construction the chain 16 is driven by power derived from the shaft 33. Near the shaft 88 a second transversely positioned shaft 95 is provided which receives power from shaft 33 which receives power through the bevel gears 96 and 97, shaft 95 having a sprocket wheel 98 rigidly secured thereto for accommodating the chain 99, which chain also passes over a sprocket wheel 100 secured to the shaft 101, which shaft carries pulleys 102 and 103 as well as the eccentric disks 104 and 105. The pulleys 102 and 103 accommodate the drive belts 106 and 107, which belts pass over the respective pulleys

108 secured to the shafts of the rotary brushes 27 and 28 whereby power is transmitted to these brushes. The eccentric disks 104 and 105 accommodate eccentric straps 109 and 110, said straps operating the eccentric rods 111 and 112 which in turn are secured to the respective slides 113 and 114. The shafts 115, 116, 117 and 118 are connected to these respective slides and accommodate the respective rollers 119, 120, 121 and 122, which rollers accommodate the respective aprons of card cloth 23 and 24. By this construction and arrangement, the aprons 23 and 24 are reciprocated or moved back and forth longitudinally of the teasel frame 18 while the aprons are caused to travel by reason of the fact that the rollers 119 and 121 are continually driven during the operation of the machine. As the card cloth aprons become easily clogged with wool flakes or raveling, they need continual cleaning which is effected by the brush rollers 27 and 28. These rollers rotate at a comparatively high speed and brush the lint and flakes from the card cloth aprons 23 and 24 during the operation of these aprons. Each of the shafts 115 and 117 is provided with a sprocket wheel for accommodating the respective sprocket chains 123 and 124 which pass over suitable sprocket wheels 125 and 126, said last mentioned sprocket wheels being rigidly secured to the vertical shafts 127 and 128, which shafts extend downwardly and through suitable bevel gears 129 receive power from the respective shafts 33 and 34 through the bevel gears 130 and 131. The back and forth movement of the slides 113 and 114 is not very great and, consequently, the looseness of the chains 123 and 124 will compensate for this slight movement without causing a disconnection of the respective parts. The shaft 34 receives its power through shaft 132, bevel gears 133, 134, 135 and 136, gear 136 being rigidly connected with shaft 33. The sprocket wheel 137 is connected to the shaft 132 and accommodates the chain 138, which chain passes over the sprocket wheel 139 rigidly secured to the shaft 140 whereby said shaft is driven. The shaft 140 acts to drive the pulley wheels 141 and 142 which carry suitable belts 143 designed to engage the respective pulley wheels 144 secured to the lower end of the shafts carrying brushes 59 and 60 whereby these brushes are rotated. Power is taken off the shafts 33 and 34 respectively for rotating the brushes 25 and 26. From Figures 1, 3 and 5, it will be noted that the chain 31 passes over a pair of guiding sprocket wheels 145 and 146 and from thence downwardly over a suitable sprocket wheel 147 secured to shaft 33. A similar structure is provided on the opposite side of the machine, namely, chain 32 extends over the

guiding sprockets 145' and 146' and from thence over the sprocket wheel 147' secured to the shaft 34. The length of these chains and the usual looseness provided, permits the brushes 25 and 26 to be raised and lowered while being rotated by these chains. At the end of the frame where belt 63 is located, the sprocket wheel 13 is mounted on a suitable shaft 84 which has a second sprocket 83 secured thereto which accommodates chain 82 and, consequently, drives this sprocket and drum 99 whereby the belt 63 will be properly driven at the required speed.

During the operation of the machine, all of the parts are functioning at the same time and the various brushes and cleaning means act upon the teasels as they pass gradually through the machine so that they are finally discharged off belt 63 in a cleaned condition though still wet. Though the teasels are wet or moist by reason of having operated on moist cloth, there is an appreciable amount of dust and dirt carried in the lint and teasels. During the cleaning operation, this dust becomes loose and would be more or less objectionable when the blast of air from cup 61 begins to function if means were not provided for accommodating the dust.

As indicated particularly in Figure 6, a hood 61' of sheet metal or other desired material is provided which encloses the various cleaning elements except for an opening at the bottom whereby when suction is applied to the outlet pipe 61", the dust removed from the teasels and lint will be

drawn off to a discharge point. The lint also will be drawn off and deposited at a suitable discharge point as otherwise it would make undesirable deposits around the cleaning machine. When they leave the belt 63 they drop upon the guide or skids 86 and by gravity slide to a discharge point.

What I claim is:—

1. A teasel cleaning machine, comprising a guideway for guiding a teasel carrying frame, means for forcing said frame along said guideway, a series of belt brushes arranged adjacent said guideway, means for moving the belt brushes to act on the teasels carried by said frame, said means causing the operating faces of the belt brushes to travel in a direction opposite to the travel of the teasels, and a set of rotating brushes acting on the teasels carried by said frame for cleaning the same as they move along said guide-way.

2. A teasel cleaning machine, comprising a guide substantially U-shaped in vertical cross section for receiving a teasel frame, means for causing said teasel frame with the teasels therein to move along said guide, a plurality of belt brushes acting on said teasels, means for driving said belt brushes so that the part thereof in contact with the teasels will move in the opposite direction to the movement of the teasel frame, and means for bodily reciprocating said belt brushes in a direction parallel to said guide while they are operating.

MAX POETZSCH.
